UNITED STATES PATENT OFFICE.

FITZLAND L. WILSON, OF SAGINAW, MICHIGAN.

HOOP-CUTTING MACHINE.

SPECIFICATION forming part of Letters Patent No. 238,467, dated March 1, 1881.

Application filed July 31, 1880. (No model.)

To all whom it may concern:

Be it known that I, FITZLAND L. WILSON, of the city and county of Saginaw, and State of Michigan, have invented an Improvement 5 in Hoop-Cutting Machines, of which the following is a specification.

My invention is designed to cut beveled strips directly from a log; and it consists of a slide, propelled by suitable mechanism, and 10 carrying two cutters at right angles to each other, and a third cutter inclined to both.

My invention further consists in certain details of construction hereinafter more fully set forth.

15 Figure 1 is a perspective view of my improved machine. Fig. 2 is a vertical cross-section.

In the accompanying drawings, which form a part of this specification, A is a stationary 20 guide of suitable length, and it is securely bolted or fastened to a proper frame.

B is a slide having a reciprocating movement along the guide, and held thereto by proper cheeks a, or other devices to that end. 25 Friction-rollers might be properly employed to relieve the friction connected with this motion. The slide B consists of the vertical upright part b and a projecting horizontal flange or lip, c. To the vertical part of this slide 30 are secured and project therefrom the cutter-knives, d d, arranged in pairs, and one of each pair in advance of the other, as shown. Two such pairs are employed, and between these two sets of knives, and fastened in a vertical 35 position to the front of the flange c is the double cutter-knife d'.

By an examination of Fig. 2, where C represents a section of a log, it will be observed that the relative position of each set of knives 40 to the double cutter d' is such that their combined action upon the log (the slide being supported in motion) will cut therefrom a pair of bevel hoops at each stroke, the second set of knives being reversed to the first cutting-knives, and cutting at the return-stroke. The 45 log C in this case is fed to the knives by any of the known mechanical appliances adapted

to that purpose, the slide B having no other movement besides its reciprocating one. This mode of cutting hoops will naturally compress 50 the timber between the knives and between the knives and the parts or flanges b c. To relieve such compression, which if not provided for would render the whole device impracticable, I countersink all or such portion of the 55 flanges b and c as are opposite the knives to such a degree as will relieve such compression and allow the hoops to be easily cut. In Fig. 1 this countersunk portion m is shown to extend in the flange c from e to f, and the countersink n in the upright part b is shown to extend from g to h. The slide is driven in its reciprocations by any convenient power.

What I claim as my invention is—

1. A slide having suitable propelling mechanism and carrying two cutters at right angles to each other, and a third cutter inclined to both the other cutters, substantially as described, and for the purpose set forth. 65

2. A slide having suitable propelling mechanism and countersunk as described, and carrying two cutters at right angles to each other, and a third cutter inclined to both the other cutters, substantially as described, and for the purpose set forth. 70

3. The combination, with the guide A, of the slide B, having the flange c, cutter d', secured to said flange, and cutters d d, one of the latter cutters being arranged at right angles to the cutter d', and the other cutter, d, 80 inclined to both cutters, substantially as described, and for the purpose set forth. 75

4. The combination, with the guide A and slide B, having the flange c and countersinks n m, of the cutters d d', two of said cutters 85 being arranged at right angles to each other, and the third cutter inclined to both the other cutters, substantially as described, and for the purpose set forth.

FITZLAND L. WILSON.
